UNITED STATES PATENT OFFICE.

JOHN CALLAHAN, OF DURANGO, COLORADO.

BUILDER'S JACK.

SPECIFICATION forming part of Letters Patent No. 494,842, dated April 4, 1893.

Application filed August 18, 1892. Serial No. 443,395. (No model.)

To all whom it may concern:

Be it known that I, JOHN CALLAHAN, of Durango, in the county of La Plata and State of Colorado, have invented a new and Improved 5 Builder's Jack, of which the following is a full, clear, and exact description.

My invention is an improved jack for carpenters' or builders' use, it being particularly adapted for squaring or adjusting window frames, or sashes, and for other analogous purposes.

The invention consists in the novel construction and combination of these several parts, as will be hereinafter fully set forth and 15 pointed out in the claim.

Reference is to be had to the accompanying drawings forming a part of this specification, in which similar figures of reference indicate corresponding parts in all the views.

20 Figure 1 is a side elevation of the jack. Fig. 2 is a central longitudinal section taken practically on the line 2—2 of Fig. 1; and Fig. 3 is a transverse section taken essentially on the line 3—3 of Fig. 1.

25 In carrying out the invention two sockets 10 and 11, are employed, and these sockets are preferably made rectangular in general contour, their recesses being also rectangular.

One of the sockets has integral with or attached to its inner end a hub 12, and this hub is interiorly threaded to receive the threaded end of a screw 13, the head portion of which screw is swiveled in the inner end section of the opposing socket 10, and the screw is manipulated in such manner as to bring the sockets in direction of each other or carry them a required distance apart, through the medium of a head 14, having radial projections which as is shown in Fig. 3, is firmly attached to the 35 neck of the screw. This head preferably con-

sists of a circular or disk-like body 15, from which arms 16, radiate, the arms being adapted to be grasped by the operator to facilitate the turning of the head and consequently also the turning of the screw.

45 In the side of each socket 10 and 11 a set screw 17, is located, and this set screw may, when desirable, be carried through openings 18, produced in the sides of the sockets opposite those in which the set screws are supported. The sockets are adapted to hold or to receive any object capable of entering them; and when the tool is employed in straightening a window frame or window sash, for instance, blocks 19, are located in the sockets, 50 being held therein by the set screws 17, and the outer ends of the blocks are beveled, as shown in dotted lines in Fig. 2. When so used the jack is placed diagonally of the frame, the beveled ends of the blocks 19 entering diagonally opposite corners of the frame; and by the manipulation of the head 14 the sockets are forced far enough apart to bring the frame or sash operated upon into perfect rectangular shape.

60 Having thus described my invention, I claim as new and desire to secure by Letters Patent—

The carpenter's jack composed of the two sockets 10 and 11 having rectangular recesses 70 and open at their outer and opposite ends, a set screw working through one side of each socket, a screw 13, and a head 14, secured to the screw and connecting the two sockets adjustably as shown and described.

JOHN CALLAHAN.
